UNITED STATES PATENT OFFICE.

CLOVIS GAMACHE, JR., OF NASHUA, NEW HAMPSHIRE.

DESIGN FOR A FRAME OR PLAQUE.

53,577.

Specification for Design.

Patented July 15, 1919.

Application filed January 4, 1918. Serial No. 210,391. Term of patent 3½ years.

To all whom it may concern:

Be it known that I, CLOVIS GAMACHE, Jr., a citizen of the United States of America, residing at Nashua, in the county of Hillsborough and State of New Hampshire, have invented a new, original, and ornamental Design for Frames or Plaques, of which the following is a specification, reference being had to the accompanying drawing, forming part thereof.

The figure is an elevational view of a frame or plaque illustrating my new design.

The design may be applied to said articles by being printed, painted, stamped, cast or embossed thereupon or otherwise, according as the case may be.

I claim:

The ornamental design for a frame or plaque, as shown.

Signed at Boston, in the county of Suffolk and State of Massachusetts, this 31st day of December, 1917.

CLOVIS GAMACHE, JR.
